UNITED STATES PATENT OFFICE.

PAUL PAGAC, OF CHICAGO, ILLINOIS, ASSIGNOR TO ROBERT HENRY PARRY, OF CHICAGO, ILLINOIS.

ATTACHMENT FOR SEWING MACHINES.

Application filed February 16, 1924. Serial No. 693,193.

To all whom it may concern:

Be it known that I, PAUL PAGAC, a citizen of the United States, residing at Chicago, in the county of Cook and State of Illinois, have invented certain new and useful Improvements in Attachments for Sewing Machines.

This invention relates to attachments for sewing machines. It is a common complaint in shops using a number of sewing machines, in schools for teaching the making of clothes and the like arts, and in other such establishments, that a great deal of time is lost by the changing of spools from one color of thread 15 to another when working on various colors of material.

It is a still further complaint that theft of thread and spools is very common and amounts to a very large aggregate. Therefore, the invention has for one of its principal objects the provision of a device for holding a plurality of spools of thread in such a position that any one of them may be used without removing the others from 25 the machine.

Another important object is to provide such an attachment made to fit any standard sewing machine without necessitating any change in the structure of the machine.

Another important object is to provide means for locking the spools of thread upon the machine so as to prevent theft thereof.

Another object is to provide an attachment which may be readily removed from a machine, if desired.

A still further object is to devise an attachment which will be inexpensive to manufacture.

Other objects will be in part apparent and 40 in part pointed out in the course of the description.

Referring now to the drawings forming a part of this specification,

Fig. 1 is a view in elevation of a head of 45 a sewing machine with my attachment thereon.

Fig. 2 is a plan view of my attachment in place.

Fig. 3 is a view partly in section on the 50 line 3—3 of Fig. 2.

The numeral 1 designates a conventional

head for a sewing machine of any standard make. Such heads commonly have an aperture 2 in the top thereof to receive a pin on which is usually mounted a spool of thread, 55 and at the other end thereof means for stitching, indicated generally at 3. Mounted upon the top of the head is my improved attachment which consists essentially of a metal plate 4 having mounted therein by 60 any suitable means, as by screw threads 5, a plurality of pins 6. The plate 4 is attached to the head at one end by a link 7 having one end 8 pivotally mounted in the plate 4 and having the other end 9 occupying the 65 aperture 2 in the head 1, the pin usually occupying this aperture having been removed. The other end of the plate 4 is attached to the head by means of a clamp 10, embracing the head as shown, and adapted to be tightened 70 thereon by any suitable means, as by a bolt 11, as plainly shown in Fig. 3. The pins 6 are of such a size and are so spaced as to support a plurality of spools of thread, and at their upper ends, at a height sufficient to 75 clear the spools, these pins are apertured as at 12, the apertures 12 being in alignment and receiving a slidably locking bar 13. The locking bar has one end enlarged as at 14 to prevent passage through the pins 6, and its 80 other end has suitable locking means thereon, in this embodiment, said locking means being exemplified by an aperture 15, receiving a padlock 16. It will be noted that the link 7 will permit adjustment of the entire 85 attachment so that the central line of the attachment may be placed at an angle to the longitudinal center line of the machine head 1. By means of this arrangement, it will be readily seen that thread may be unwound 90 from any of the spools and led to the stitching means 3.

In the embodiment illustrated, I have shown five pins 6 and locking means to keep the spools on four of the pins. I prefer this 95 construction because it permits the use of a number of the spools of colors which are commonly used and those spools are locked in place. I prefer to leave the one pin 6' unlocked so that a spool of thread of some 100 special color, which is only used occasionally, may be readily placed on or removed from

this pin without the trouble of unlocking all the spools which are used.

The pin 6" is screw-threaded into a block 17 which receives the bolt 11 to tighten the 5 clamp 10. This pin 6" is not threaded into the plate 4, merely passing therethrough, thereby permitting pivotal adjustment of the plate 4 to any position desired.

From the above description, it will be apparent that I have devised an attachment 10 which may be easily applied to or removed from any sewing machine of standard make without involving any change in the structure of the machine other than the removal 15 of a small pin, which removal is easily effected.

The bolt 11 is reduced for a portion of its length, as shown at 18, and this portion may be round, square, or of any other suitable 20 shape, whereby when it is engaged by the pin 6", the bolt 11 will be locked against removal. Means is thus provided for locking the entire attachment to the sewing machine. When the attachment is to be placed 25 on the machine, the clamp 10 is first put in place, the bolt 11 is then passed through the openings in the upper ends and threaded through the block 17. The link 7 of the plate 4 is then placed in position with its 30 end 9 in the aperture 2, the pin 6" is passed through its opening in the plate 4 and screwed tightly into the block 17. The spools are then placed in position on the pins 6, 6' and 6", the locking bar 13 is 35 passed through the aligned opening 12 in the pins, and the padlock 16 placed in position. It will thus be seen that the attachment is securely locked to the sewing machine, and can not be removed therefrom 40 without first removing the padlock 16.

It will be further apparent that my attachment is cheaply made and will effectively support a plurality of spools of thread in such a position that thread may be un wound from any one for use in the machine, and that as many spools as desired may be effectively locked in position to prevent theft.

I am aware that changes in the form and 50 proportion of parts in details of construction of my invention may be made without departing from the spirit or sacrificing the advantages of the invention, and, therefore, I reserve the right to make all such changes 55 as fairly fall within the scope of the following claims; for example, it is obvious that the locking bar 13 may be made to lock as many or as few spools as is desirable and that any other locking means may be substituted for the padlock 16 and bar 13.

I claim:

1. An attachment for sewing machines comprising a member adapted to be clamped at one end to a sewing machine head and 65 adjustably mounted at the other end to said

head whereby said attachment may be disposed at an angle to said head for the purpose set forth.

2. An attachment for sewing machines comprising a plate, a clamp at one end of 70 said plate, a link at the other end of said plate, and spool supporting means on said plate.

3. An attachment for sewing machines comprising a plate, a clamp at one end of 75 said plate, a link at the other end of said plate, spool supporting means on said plate, and means for locking said spools on said spool supporting means.

4. In combination, a sewing machine 80 head, a plate clamped to said head at one end thereof and adjustably connected thereto at the other end for pivotal movement about said first end, pins on said plate to support spools, and means for locking said 85 spools on said pins.

5. A device of the character described comprising a supporting plate, a clamp at one end of said plate, a pivoted link at the other end thereof, a plurality of pins screw-threaded in said plate, certain of said pins having aligned apertures, a locking bar passing through said apertures, and means to lock said bar in position. 90

6. An attachment for sewing machines 95 comprising means for holding a plurality of spools in position for use on a sewing machine, and means for locking said attachment on said sewing machine.

7. In an attachment for sewing machines, 100 means for holding a plurality of spools in position for use on a sewing machine, means for locking said spools in position, and means for locking said attachment on said sewing machine.

8. An attachment for sewing machines comprising a plate, a clamp at one end of said plate, spool supporting means on said plate, a block supporting said plate, a bolt passing through said clamp and threaded into said block, a portion of said bolt being reduced in diameter, and means passing through said plate to engage said reduced portion of said bolt to lock said bolt in place. 110

9. In an attachment for sewing machines, 115 means for fastening said attachment to a sewing machine head, and means to support a spool on said attachment, said supporting means locking said fastening means.

10. In an attachment for sewing machines, means for fastening said attachment to a sewing machine head, means for supporting a plurality of spools on said attachment, and means for locking said spools on said attachment, said locking means serving to lock said fastening means. 120

11. An attachment for sewing machines comprising a plate, a clamp at one end of said plate, a block supporting said plate, a 130

bolt passing through said clamp and threaded into said block, and spool supporting means carried by said plate and passing through said plate and said block and engaging said bolt to lock said attachment.

12. An attachment for sewing machines comprising a plate, a clamp at one end of said plate, a block supporting said plate, a

bolt passing through said clamp and threaded into said block, spool supporting means carried by said plate and passing through said plate and said block and engaging said bolt to lock said attachment, and means to lock said spool supporting means.

PAUL PAGAC.
